UNITED STATES PATENT OFFICE.

HARRY W. CRANE, OF PHILADELPHIA, PENNSYLVANIA, ASSIGNOR TO INTERNATIONAL WINDOW MANUFACTURING COMPANY, A CORPORATION OF DELAWARE.

WINDOW.

1,132,652.

Specification of Letters Patent.

Patented Mar. 23, 1915.

Application filed November 19, 1913. Serial No. 801,775.

To all whom it may concern:

Be it known that I, HARRY W. CRANE, a citizen of the United States, residing at Philadelphia, county of Philadelphia, and 5 State of Pennsylvania, have invented a new and useful Improvement in Windows, of which the following is a full, clear, and exact description, reference being had to the accompanying drawings, which form a part 10 of this specification.

My invention relates to windows, and particularly to that class in which counterbalanced sashes, in addition to having a vertical movement in a window frame, are capable of swinging on a horizontal axis midway between their upper and lower ends. Such a window is set forth in the patent to 15 George, No. 776,177, dated November 29, 1904.

20 The object of my invention is to provide a construction of window capable of being constructed in its entirety, except the glass pane, of metal.

In the drawings, which show a preferred 25 embodiment of my invention: Figure 1 is a perspective of window frame, shoe and sash, all partly broken away, with the sash partly swung open. Fig. 2 is a perspective of the frame and shoe with the sash and certain 30 parts of the pivotal connection removed. Fig. 3 is a vertical section through the sash and shoe in a plane parallel to the glass. Fig. 4 is a face view of the shoe. Figs. 5, 6 and 7 are sections respectively on the lines 35 5-5, 6-6 and 7-7 of Fig. 3. Fig. 8 is an enlarged view showing a detail of my construction.

The shoe *a* is one of a pair of shoes adapted to slide in vertically-extending grooves 40 or runners in the window frame and between which is pivotally supported the sash *b* on a horizontal axis midway between the upper and lower ends of the shoes. Each shoe is made from a hollow piece of metal. 45 This hollow metal bar is of uniform width throughout measuring from the outside to the inside thereof, but is of varying and irregular depth measuring from the window frame toward the sash.

50 In its central portion (see Figs. 6 and 7) the shoe is of substantially rectangular contour and of comparatively small depth. In one end portion, say the upper end portion (see Fig. 5) the shoe is of medium width

except near its inside and outside faces. 55 Adjoining one face (say its inside face) it is of comparatively small depth, or of substantially the depth of its central portion, while near its other or outside face it has its maximum depth. In the other end portion, 60 say the lower end portion, the shoe is of medium depth except near its inside and outside faces. Adjoining one face (say its outside face) it is of comparatively small depth, or of substantially the depth of its 65 central portion, while near its other or inside face it has its maximum depth. In other words, the shoe is of maximum depth on its outside face at one end and on its inside face at its other end and is of minimum 70 depth on its inside face at the first named end and on its outside face at the last named end, while its central portion, being of minimum depth, is virtually recessed relatively 75 to the end portions, which are, as above 80 stated, of medium width except in the portions thereof adjoining the inner and outer faces. The changes in depth are abrupt, the metal being stepped, or bent substantially at right angles to the direction of extension of the shoe, to effect the variation in depth described. The sash is also a hollow metal structure and is of uniform width throughout, measuring from the outside to the inside thereof. The body thereof, except 85 along its outer and inner faces, is of uniform depth. In one end portion, say the upper end portion, the sash, near one face, say its inner face, is of maximum depth, while near its other or outer face it is of minimum 90 depth. In the other end portion, say its lower end portion, the sash, near one face, say its outer face, is of maximum depth, while near its other or inner face, it is of minimum depth. In other words, the sash 95 is of maximum depth on its outer face at one end and on its inside face at the other end and is of minimum depth on its inside face at the first named end and on its outside face at the last named end.

100 The central portion of the sash is of maximum depth along only its outer and inner faces, thus forming an inclosed longitudinally-extending space between the shoe and sash. It will thus be observed that each of 105 the two members, in its end portions, is of a three-stepped contour on the face thereof opposed to the face of the other, thus form-

ing hollow projections on each member conforming to insets on the other member; while in the central portions, the shoe and sash abut against each other adjoining their 5 front and rear faces, but a rectangular in-closed space is formed between them, which space extends above and below the central pivot. The exact fitting of the two members is effected by making the hollow pro-10 jections exactly correspond in dimensions with the insets with which they engage.

By reason of the foregoing construction, the sash may be swung on its pivot in one direction without interference between sash 15 and shoe but will be locked from swinging in the opposite direction, and when closed will present together a perfect rectangular outline (except on the side of the sash adjoining the window pane) and will be ab-20 solutely weather tight.

At the center of the central portion of the sash, the metal in the wall thereof opposite the shoe is bent to form, in connection with an annular flange on the shoe, an axial bolt-25 receiving orifice and also an annular space adapted to the reception of a filler ring *c*. A collar *d*, providing a bearing for the bolt, extends within said bolt-receiving orifice, and has a flange extending into the hollow 30 interior of the sash and underlying the wall thereof opposite the shoe. The bolt *e* extends through the collar *d*, the head of the bolt being within the hollow interior of the sash and engaging the flange of the collar *d*. 35 The other end of the bolt extends into the hollow interior of the shoe and has threaded thereon a pair of nuts *f*. A cup-shaped spring washer *g* is sleeved on the bolt within the hollow interior of the shoe and is con-40 fined between the nuts *f* and the wall of the shoe opposite to the sash. The wall of the shoe opposite the sash is offset, both above and below the bolt *e*, to form vertically ex-45 tending shallow depressions or pockets *h*. In the space between the sash and shoe, and above and below the bolt *e*, is a flanged hold-50 ing plate *i* having ridges *j* adapted to the depressions *h*. Springs *k*, confined between the sash and the holding plate *i*, hold the plate *i* tightly against the shoe, and the ridges *j* within the depressions *h*, when the sash is closed.

By the above construction, the sash is prevented from turning from its closed po-55 sition unless a degree of force is exerted suf-60 ficient to force the holding plate *i* out of its pocketed engagement with the shoe and against the tension of the springs *k*. In turning the sash, the holding plate *i* over-65 rides the non-pocketed faces of the offset part of the shoe and frictionally resists turn-70 ing, whereby the sash is held open at any angle to which it may be turned on its axis. When the sash is turned to its closing po-75 sition, or in parallelism with the shoe, the

ridges *j* are brought opposite the depressions *h* and engage therewith by the action of the springs *k*, thus holding the sash closed.

When the sash is closed, the closure is weather-tight, the only possible opening for 70 admission of air being closed by a block *m* (see Fig. 1) secured to or integral with the head of the upper end of the shoe, said block extending across the central parting bead *n* of the window frame *o* and closing 75 the space between the shoe and the upper sash *p*. The glass pane is held in place in the sash by means of a strip *r* extending across the angle between the sash and pane and confining between it and the sash and 80 pane a piece *s* of felt or similar compressible material. To further insure full closure of the window a spring detent is provided near the end of the closing members. This detent consists of a depression *t* in one of the windows, shown as in the sash, and a spring pro-85 jection in the other member, in this case the shoe, which may either be in the form of a flat spring *u*, as shown in Figs. 3 and 5, or of a spring pressed roller *v* as shown in 90 Fig. 8.

Having now fully described my invention, what I claim and desire to protect by Letters Patent is:

1. In a window, in combination, a shoe 95 which throughout a part of its length has a three-stepped contour on the face thereof opposite the sash, forming a projecting rib adjoining one face and a corresponding in-set adjoining the other face, a sash which 100 throughout a part of its length has a similar three-stepped contour on the face thereof adjoining the sash, forming a projecting rib opposite and corresponding to the inset in the shoe and an inset opposite and corre-105 sponding to the rib in the shoe, said shoe in another part of its length being of less depth than in the body of its stepped portion, said sash in the corresponding part of its length having, adjoining its inside and 110 outside faces, projecting ribs closing the space between shoe and sash, and a pivot pin connecting the shoe and sash.

2. In a window, in combination, a shoe, each end portion of which is of a three-115 stepped contour on the face thereof opposite the sash, forming in one end portion a pro-jecting rib adjoining the inside face and a corresponding inset adjoining the outside face, and in the other end portion a similar 120 rib adjoining the outside face and a corre-sponding inset adjoining the inside face, a sash of a similar three-stepped contour in its two end portions, the ribs of one member being arranged respectively opposite the insets 125 of the other member, one member in its central portion presenting a flat face and the other member in its central portion having, adjoining the inside and outside face, pro-jecting ribs closing the space between shoe 130

and sash, and means pivotally connecting the sash and shoe at their central portions.

3. In a window, in combination, two members, one a shoe which throughout a part of its length has a three-stepped contour on the face thereof opposite the sash, forming a projecting rib adjoining one face and a corresponding inset adjoining the other face, and the other a sash which throughout a 10 part of its length has a similar three-stepped contour on the face thereof adjoining the shoe, forming a projecting rib opposite and corresponding to the inset in the shoe and an inset opposite and corresponding to the rib 15 in the shoe, one of said members at another part of its length having a flat face while the other member in the corresponding part of its length has, adjoining its inside and outside faces, projecting ribs inclosing a 20 space between shoe and sash, and a pivot pin connecting the shoe and sash.

4. In a widow, in combination, two members, one a shoe which throughout a part of its length has a three-stepped contour on 25 the face thereof opposite the sash, forming

a projecting rib adjoining one face and a corresponding inset adjoining the other face, and the other a sash which throughout a part of its length has a similar three-stepped contour on the face thereof adjoining the shoe, forming a projecting rib opposite and corresponding to the inset in the shoe and an inset opposite and corresponding to the rib in the shoe, one of said members at another part of its length having 30 projecting ribs adjoining both its inside and outside faces, while the other member has a face spaced from the face between the ribs of the first member, thereby forming an inclosed space between shoe and sash, 35 and a pivot pin connecting the shoe and sash and extending into said inclosed space.

In testimony of which invention, I have hereunto set my hand, at Philadelphia, on this 28th day of October, 1913.

HARRY W. CRANE.
